COPYHOLDER

Roy S. Hopkins, Rochester, N. Y., assignor to
 Eastman Kodak Company, Rochester, N. Y., a
 corporation of New Jersey

Application October 21, 1938, Serial No. 236,286

2 Claims. (Cl. 281—6)

The present invention relates to a copyholder and more particularly to a copyholder which is suitable for holding in a flat condition large drawings, maps, etc. which have been stored in rolls.

5 It is well recognized that maps or drawings which have been rolled for any length of time have acquired a "set" and that it is exceedingly difficult to lay such documents flat either for inspection or for copying purposes.

10 The primary object of the present invention is the provision of a simple and effective copyholder which can be easily operated by one person to unroll and maintain a map or drawing in a flat position upon a plane support.

15 Another object of the invention is the provision on a copyholder of a movable assembly which is supported by rolling means for parallel movement and which can be readily moved along the copy support or toward or away from the 20 document thereon.

25 A further object of the invention is the provision on a copy support of a pair of toothed racks and of a movable assembly including a document-engaging member and a pair of connected pinion gears in engagement with the racks, the document-engaging member being movable to hold the document against the support and/or being movable along the support to engage different portions of a large document.

30 Other and further objects of the invention will be suggested to those skilled in the art by the description which follows.

The above and other objects of the invention are embodied in a copyholder comprising in combination a support for a document, guide members, such as toothed racks, in spaced relation on said support, a movable assembly including a document-engaging member, and rolling means, such as pinion gears, connected together on said 35 movable assembly and in rolling engagement or in mesh with said guide members for supporting the assembly over the support and for maintaining said assembly in parallelism during movement along the support.

40 45 Reference is hereby made to the accompanying drawing wherein like reference characters designate similar elements and wherein:

Fig. 1 is a plan view of the copyholder of the invention.

50 Fig. 2 is a side elevation of such a copyholder.

Fig. 3 is a fragmentary cross section taken on the line 3—3 of Fig. 2.

In the illustrated embodiment of the invention, the copyholder comprises a support 10 which may conveniently be provided as the top 55

of a table. A pair of guide members are mounted in spaced relation on said support 10 and in the preferred form of the invention constitute a pair of toothed racks 11.

A movable assembly according to the invention 5 includes a movable document-engaging member which may be moved toward or away from the document upon the support 10 and which is also movable with the assembly to engage different portions of a document or documents of different 10 dimensions. Such a movable assembly may comprise a shaft 13, carrying a sleeve 16 to which the document-engaging member 17 is attached by a plurality of screws 19. Said sleeve 16 may rotate freely on the shaft 13 and the document- 15 engaging member 17 extends to one side of the sleeve 16 so as to be unbalanced and normally to be urged by gravity toward the surface of support 10.

Rolling means are connected together on the 20 aforementioned movable assembly and are in rolling engagement with the spaced guide members both to support the assembly over the support 10 and to compel movement in parallelism of said movable assembly along said support 10. 25 Such rolling means may be in frictional engagement with the guide members but are preferably provided as pinion gears 12, each fastened by set screws 12' to the shaft 13 and each in positive engagement or meshing with the teeth of the 30 racks 11. Since both of said pinion gears 12 are fastened to the shaft 13 it will be clear that the shaft 13 and the document-engaging member 17 will be maintained in parallelism during movement along the support 10 and over 35 the toothed racks 11.

Although not essential to the invention, it is considerably more convenient to provide guide means on the movable assembly for maintaining the rolling means, such as the pinion gears 12, in engagement with the guide members or toothed racks 11. Such a guide means may comprise end plates 14 journaled over each end of the shaft 13 and held in place thereon by collars 14'. A pair of rollers 15 are rotatably mounted upon each of the end plates 14 for engagement with the guide members or toothed racks 11 to hold the movable assembly and the rolling means thereof in engagement with said guide members.

50 A manual means is also mounted on the movable assembly and may comprise a handle 18 fastened to the document-engaging member 17. Such a manual means or handle 18 will serve a dual purpose, first it may be rotated to cause 55

rotation of document-engaging member 17 and its movement toward or away from the surface of support 10. By such rotation of handle 18 the documents may be held against support 10 or may be released for removal from the same. Also the handle 18 may be moved along the support 19 in a longitudinal direction to change the position of the entire movable assembly with respect to the support 10 and document thereon. Such longitudinal movement of the movable assembly may be accomplished either with the member 17 in engagement to hold a document against the support 10 or in spaced relation and out of contact with the document on the support 10. The operation of the copyholder and particularly the pair of movable assemblies for easy handling of large rolled documents will now be explained. One end of the rolled document is inserted under the shafts 13 or sleeves 16 of the movable assembly. The pair of movable assemblies may be moved close together to facilitate this operation and it will also be understood that the guide means composed of end plates 14 and rollers 15 will prevent displacement or disarrangement of the movable assemblies during such threading or insertion of the end of the document under the movable assembly. This condition of the rolled document R is illustrated by the dot-dash lines in Fig. 2.

The operator now has several options, first, one handle 18 of one movable assembly may be pressed firmly to hold the document securely against the support 10 and the other handle 18 may be rotated to press member 17 and the document against the support but at the same time may be moved along the support 10 simultaneously to unroll the document and to flatten it against the support. It is, of course, understood that at all times the movable assemblies must move in parallelism or with the edges of document-engaging members 17 parallel to each other. Thus the documents may be unrolled or any section of them may be flattened against the support 10.

Since many variations of the invention are

possible, the scope of the invention is to be determined only by the appended claims.

Having now particularly described my invention what I desire to secure by Letters Patent of the United States and what I claim is:

1. In a copyholder for documents, the combination with a document support, and guide members in spaced relation on said support, of a pair of independently movable assemblies each including a pair of rolling members connected together and respectively engaging said guide members, and each including a document engaging member normally urged toward said support to hold a document thereagainst and movable along said support in perpendicular relation to said guide members, each of said document members being maintained in parallel relation to each other by engagement of said rolling members with said guide members whereby said document engaging members are held against a portion of a curled or rolled document and either of said document engaging members is moved away from the other to smooth and/or hold said document in flat position on said support. 20

2. In a copyholder for documents, the combination with a document support having opposite edges and a pair of stationary racks each mounted along one of said edges of said support, of a pair of movable assemblies each comprising a shaft, pinion gears fixed to opposite ends of said shaft and each in engagement with one of said racks, and a document engaging member journaled on said shaft and normally urged toward said support to hold a document thereagainst, each of said assemblies being independently movable with said document engaging members perpendicular to said guide members and parallel to each other whereby said document engaging members may be brought adjacent each other over a curled or rolled document and either of said document engaging members may be moved away from the other to smooth and hold at least a portion of said document flat on said support. 40

ROY S. HOPKINS. 45
